DESIGN FOR A POTATO CUTTER

John S. Garner, Darlington, S. C.

Application May 14, 1945, Serial No. 119,539

Term of patent 7 years

(Cl. D89—1)

To all whom it may concern:

Be it known that I, John S. Garner, a citizen of the United States, residing at Darlington, in the county of Darlington and State of South Carolina, have invented a new, original, and ornamental Design for a Potato Cutter, of which the following is a specification, reference being had to the accompanying drawing, forming part thereof.

I claim:

The ornamental design for a potato cutter, as shown.

JOHN S. GARNER.
